PAPER NAPKIN

Louis Thomas Volo, New York, N.Y., assignor to The Procter & Gamble Company, Cincinnati, Ohio, a corporation of Ohio

Filed May 19, 1969, Ser. No. 17,211

Term of patent 14 years

Int. Cl. D5—03

U.S. Cl. D59—2

The figure is a fragmentary plan view of a paper napkin showing partial edges and one corner thereof. The remaining corners and edges exhibit the same design as the partial edges and corner shown. The paper napkin is dimpled throughout except in the areas of the petals.

I claim:

The ornamental design for a paper napkin, as shown and described.
